UNITED STATES PATENT OFFICE.

HERBERT B. TAYLOR, OF NEWARK, NEW JERSEY.

RAILWAY BLOCK-SIGNALING SYSTEM.

SPECIFICATION forming part of Letters Patent No. 739,518, dated September 22, 1903.

Application filed August 2, 1901. Serial No. 70,636. (No model.)

To all whom it may concern:

Be it known that I, HERBERT B. TAYLOR, a citizen of the United States, residing at Newark, in the county of Essex and State of New Jersey, have invented certain new and useful Improvements in Wireless Cab Block-Signal Systems, of which the following is a specification.

This invention relates to improvements in wireless cab block-signal systems, the object being to provide a block-signal system embodying all the essential features of any standard system now in use and at the same time avoiding defects relative to such signals to which objection can be made.

The system may be called a "wireless cab block-signal" system, from the fact that all line-wires are dispensed with, no wires of any kind being used except those connecting the signal with the rails, and to attain this object I intend employing such apparatus as has already been described in previous patents of my own, together with such other apparatus as is or has been in practical use for wireless signaling purposes, this combination being novel and useful.

The description is as follows: A railway-track is divided into blocks or sections which are electrically insulated one from another in a manner usual in signal practice, each section including a source of electrical energy, thus forming a track-circuit. A device controlled by the track-circuit of a section is arranged and adapted to operate a transmitting device which is located at or near the junction of two of the said sections. The said transmitting device on being energized will send electrical waves or oscillations out through space—that is, through the surrounding medium. A sensitive receiver may be located at any suitable place for observation along the track or may be placed on the moving train. This receiver is adapted to be influenced by the waves or oscillations produced by the said transmitting device. As objection is made in some cases to visual signals placed along the track, which may be obscured by snow or fog, I prefer in such cases to locate the receiver on the train. The signal on the train or cab of the engine may be visual or audible, preferably the former, and is controlled by the said receiving device,

and the engineer or train-runner is governed by the said signal instead of looking ahead for a track-signal and is therefore able to maintain a regular speed in storm or fog.

In the accompanying drawings, Figure 1 is a diagram of a portion of a track provided with my signaling system. Fig. 2 shows a modification thereof. Fig. 3 shows in detail the apparatus provided for propagating or transmitting electrical waves or oscillations under control of the track devices.

In Fig. 1, A-B-C are the blocks or sections into which the railway-track is divided. 1-2-3 are the sources of electrical energy for the respective sections A, B, and C. The negative rail of the sections may be grounded. Magnets 4, 5, and 6 are of high resistance (twenty ohms) and are normally energized by batteries 1, 2, and 3. The contacts 7-8-9 are normally held open, thus making the circuits of sections A-B-C open track-circuits. Magnets 10-11-12 are in shunt relation to magnets 4, 5, and 6 and are of low resistance, (one ohm.) At the opposite ends of sections B and C from the source of energy are located magnets 13 and 14, connected across the rails of their respective sections, but including, respectively, the contacts 7 and 8. Magnets 13 and 14 are of medium resistance (five ohms) and are in series relation to batteries 2 and 3—i. e., magnet 13 is in series with battery 2 and with magnet 11, and magnet 14 is in series with battery 3 and magnet 12—so that the resistance of the completed track-circuit of sections B and C (exclusive of rails and battery) is six ohms. The contacts 7 and 8, however, being normally open, the track-circuits become deenergized track-circuits. At the junction of the sections A and B is erected a pole or other support D, to which is fixed a suitable device for propagating or transmitting electrical waves or oscillations during the entire time that said device is in operated or controlled condition. Such device may be of any approved type, but would generally contain a primary electric circuit and source of energy and also a secondary circuit which is adapted to become energized by induction from the said primary and to impart or transmit the said oscillations upon becoming so energized, one part of said secondary circuit being connected to ground. As this device

must transmit the waves or oscillations as long as the controlling-circuit remains energized, it is necessary to provide an induction device which will operate continuously during such conditions. Such a device is shown in Fig. 3, consisting of an induction-coil 21, having its primary connected through the circuit-breaker 22 and the energizing-battery 23 to the local circuit 24, controlled by the armature 15, while the secondary of such induction-coil is connected, on one hand, to ground and, on the other hand, to the transmitting conductor or terminal 26. The circuit-breaker 22 referred to is controlled magnetically by the induction-coil in the usual manner, so as to continually make and break the circuit, and thereby cause the induction of current impulses in the secondary circuit, which impulses are transmitted through the device 26 to the surrounding atmosphere as electrical waves or oscillations. The primary circuit of the transmitting device is normally open at contact 15 and is controlled by magnet 4 of section A and magnet 13 of section B. Magnet 4 normally holds open the contact 15. Therefore as long as the primary circuit is open at 15 there is no wave transmission. On section A are wheels and axle F, intended to represent a train bridging the rails of said section. To some part of said train F, preferably to the front of the engine-pilot, is fixed a staff G, insulated therefrom and as high as the stack. To this said staff is fixed the sensitive receiving device, which may be of any approved type and must be adapted to be influenced by the electrical oscillations which proceed from the stationary transmitter D in advance of the train F. The said receiver must also be adapted to control the circuit of a signal located on the said train, preferably the engine-cab. I show a signal which is normally in a safety or clear position and which will assume the danger position upon the train entering upon a defective track-circuit or for any other reason that would cause the receiver to become deenergized. The normal condition of the various circuits is as follows: Battery 1 is energizing high-resistance magnet 4, holding open contact 15 of the primary circuit of signal-transmitter D. Battery 2 of section B is similarly energizing magnet 5. Contact 7 in the track-circuit of section B is open, owing to the deenergization of magnet 10 of section A, and therefore no current flows through the track-circuit and magnets 11 and 13 of section B. The signal devices located on the train (which has not entered upon a controlled section) may be assumed to be deenergized and the signal-disk in the danger position.

The operation is as follows: Upon train F entering controlled section A a low-resistance bridge is established across the rails of said section, and the current from battery 1 is divided proportionately between the circuit through relay 4 and the circuit through relay 10 with the rails of section A. As the

circuit through relay 10 (which has a resistance of one ohm) and the rails is of much lower resistance than the circuit through relay 4, (which has a resistance of twenty ohms,) most of the current from battery 1 will flow through magnet 10, energizing it and closing contact 7 of the track-circuit of section B. Upon the closure of contact 7 current from battery 2 of section B will flow through relay 13, which bridges said rails, thus energizing relay 13. As the total resistance of this last-defined circuit is much less than the resistance of the circuit through relay 5, a greater part of the current from battery 2 will thus flow through magnet 13, and the pull exerted on the armature 15 by magnet 13 will be more than sufficient to overcome the attraction of magnet 4 of section A for the said armature. Thus the contact 15 will be closed. Upon the closure of contact 15 the primary circuit of the transmitter D is energized, and by induction the secondary circuit produces waves or oscillations which will be propagated through space. The condition of the signal devices on the train F will be changed upon the entrance of the said train upon the section A. The receiver G is so influenced by the waves which are produced by the transmitter that the magnet of the signal H is energized, causing the signal to assume the safety position, which indicates that section B is clear. As the train F reaches section B magnet 13 becomes short-circuited, owing to the bridging of the rails of section B, and as the said magnet no longer exerts a pull on armature 15 the said armature is drawn against its back-stop by the magnet 4, which is still weakly energized. This action opens the primary circuit of transmitter D, and the electrical waves are no longer produced by transmitter D. Similarly as in section A upon bridging the rails of section B the magnet 11 at the advance end of said section now becomes energized, owing to the decrease of resistance in the rail-circuit, the resistance of which was six ohms. By cutting out relay 13 at the entrance end of section B, whose resistance is five ohms, magnet 11, which has a resistance of one ohm and was in series with magnet 13, now becomes powerfully energized and closes the track-circuit of the section C, said circuit controlling the primary circuit of the transmitter E. It will be seen that the train-signal H does not change its position upon entering a new section unless circuits of the track or transmitter are out of order or sections are occupied. Any derangement of the several devices will cause the signal H to assume a danger position, thus assuring absolute safety in running trains. As the wave-signals may be transmitted through storms or fog as well as during clear weather, the value of this invention will be plainly apparent. Although I have shown the receiving device as located on a moving train, there is no reason why it cannot be located at any convenient place along the track, if so desired.

Fig. 2 represents the signal placed in fixed position near the track convenient for observation. In Fig. 2 the arrangement of circuits and devices are somewhat different. A, 5 B, and C are the sections; batteries 1, 2, and 3 the sources of energy. D and D' are the transmitters; F, the wheels and axle, short-circuiting section A. H is the signal for section B, and H' is the signal for section C. G 10 is the receiver for section B, and G' is the receiver for section C. Relays 13, 17, and 11 are in series relation to battery 2 of section B, and relays 14, 18, and 12 are in series relation to battery 3 of section C. Relays 16, 15 10, and 13^a are similarly connected to battery 1 of section A.

The operation is as follows: Upon the short-circuiting of section A relay 13^a at the entrance end is short-circuited and relays 16 and 10 alone are energized. Owing to the low resistance of relay 10, which may be one ohm, it did not normally exert sufficient pull on the contact 7 to close the circuit of section B; but when relay 13^a of five ohms is short-circuited relay 10 becomes strongly enough energized to close the said circuit. Upon the closure of the said circuit relays 13 and 17 become energized and relay 13 closes the circuit of receiver G for signal H at point 15. This 25 signal is actuated by the receiver G, which in turn is actuated by transmitter D'. Relay 17 closes the primary circuit of transmitter D', which is then put in operation and produces electrical oscillations. Relay 11 has 30 not as yet become sufficiently energized to close the circuit of the advance section. If, however, at this time there is a train on section B, magnet 13 will be short-circuited thereby, contact 15 will be open, and the signal will not be operated. Relays 13 and 17 should both be of higher resistance than 11, so that when the circuit is closed through all 35 these relays relay 11 is not energized owing to the high resistance of the other relays; but when relay 13 is short-circuited by entrance of a train on the section then sufficient current will pass in this circuit to energize relay 11 and control the next section. It will be noted that any transmitter cannot influence 40 any receiver except the one on the same section, the other receivers being open-circuited.

One advantage of the system above described, wherein the signaling device is located on the train itself, is that after a train 45 has entered a block indicated as "safe" it is still open to receive signals indicating subsequent actions, such as opening of a switch, rendering the block dangerous. For example, the opening of a switch would break the 50 track-circuit and stop the transmission of "safety" impulses.

Having thus described my invention, the following is what I claim as new therein and desire to secure by Letters Patent:

65 1. In a wireless cab block-signal system, the combination of a track divided into blocks or sections, track-circuits for the blocks,

source of electrical energy for each of said track-circuits, devices located in the vicinity of the track and controlled by said track-circuits for producing electrical oscillations during the entire time that said devices are in operated condition and for transmitting without other conductors the said oscillations through the surrounding medium, and a signal suitably located and adapted to indicate the condition of the said blocks or sections through the influence of the said electrical oscillations. 75

2. In a wireless cab block-signal system, 80 the combination of a track divided into blocks or sections, a device located near the track, and adapted to produce electrical oscillations in the surrounding medium during the entire time that said device is in operated condition, 85 a signal adapted to be actuated by the said oscillations and indicating the condition of the track in advance of a train, and track devices connected with each of said blocks or sections and controlled by the movement of the said 90 train for causing the production and propagation of the electrical oscillations which actuate the signal and a source of electrical energy for operating said track devices.

3. In a wireless cab block-signal system, 95 the combination of a track divided into blocks or sections, a device located near the track and adapted to produce electrical oscillations in the surrounding medium during the entire time that said device is in operated condition, a signal located on a train and adapted to be actuated by the said oscillations and indicating the condition of the track in advance of said train, and track-circuits controlled by the movement of the said train 100 and controlling the aforesaid oscillation-producing devices for causing the production and propagation of the electrical oscillations which actuate the signal and a source of electrical energy for each of said track-circuits. 105

4. In a wireless cab block-signal system, the combination of a track divided into blocks or sections, devices for transmitting electrical impulses through space without wires, located along the track, said devices being 110 adapted and arranged to transmit such impulses during the entire time that said devices are in operated condition, a receiver for the said impulses located on a moving train, means adjacent to the track controlled automatically by the said train for transmitting and receiving the said impulses, and a signal on the said train for indicating the condition of the track-sections, actuated by the operation of the transmitting device. 115

5. In a wireless cab block-signal system, the combination of a track divided into blocks or sections, electric wave or oscillation-producing devices, located at or near the junction of two sections for transmitting electric 120 waves through the surrounding medium during the entire time that said devices are in operated condition, a device adapted to be energized by the said electric waves located 125

on some part of a train, and track-circuits for each section controlling the electric wave-producing devices and adapted to cause the operation of the said devices upon the entrance of the train on the said track-circuits and a source of electrical energy for each of said track-circuits.

6. In a wireless cab block-signal system, the combination of a track divided in blocks or sections, a transmitter located adjacent to the junction of two sections and capable of producing electrical oscillations in the surrounding medium during the entire time that said devices are in operated condition, a receiver located on a train and adapted to be energized by such electrical oscillations, a signal dependent upon the energization of the said receiver also located on the said train, and a track-circuit for controlling said signal arranged to operate said signal upon the entrance of the train on the track-circuit, or the exit of the train from the track-circuit and a source of electrical energy for the track-circuit.
7. In a wireless cab block-signal system, the combination of a track divided into blocks or sections, devices for transmitting electrical impulses without wires through the surrounding medium during the entire time that said devices are in operated condition and located at the junction of two sections, a device for receiving the said electrical impulses, located on a train, and controlling a signal capable of indicating the condition of a track-section in advance of the transmitting device, and track-circuits for each block for actuating the said transmitting devices, said track-circuits being controlled by the movement of the said train on the different track-sections and a source of electrical energy for each track-circuit.
8. In a wireless cab block-signal system, the combination of a track divided into blocks or sections, devices, located at or near the junction of two sections and adapted to produce electric waves in the surrounding medium during the entire time said devices are in operated condition, a device adapted to be energized by the said electric waves; and track-circuits for each section controlling the electric-wave-producing devices and adapted to cause the operation of the said devices upon the entrance of the train on the said track-circuits and a source of electrical energy for each track-circuit.
9. In a wireless cab block-signal system, a track divided into blocks, each block constituting a track-circuit, devices near said

blocks for propagating electrical oscillations through space, energizing-circuits for said oscillation devices, relays in said track-circuits for controlling said energizing-circuits, said relays controlled by a train in a preceding block, and a receiving device responsive to said oscillations suitably arranged to give notice of the condition of the block in advance of the train.

10. In a wireless cab block-signal system, a track divided into blocks, each block constituting a track-circuit, devices near said blocks for propagating electrical oscillations through space, energizing-circuits for said oscillation devices, relays in said track-circuits for controlling said energizing-circuits, said relays controlled by a train in a preceding block, and a receiving device responsive to said oscillations suitably arranged on said train to give notice of the condition of a block in advance of the train.

11. In a wireless cab block-signal system, a track divided into blocks, each block constituting a track-circuit, devices near said blocks for propagating electrical oscillations through space, energizing-circuits for said oscillation devices, relays in said track-circuits for controlling said energizing-circuits, said relays being of different resistances, the relay of higher resistance controlling the energizing-circuit of the propagating device and the relay of lower resistance controlling an advance track-circuit, said relays controlled by a train in a preceding block, and a receiving device responsive to said oscillations suitably arranged to give notice of the condition of a block in advance of the train.

12. In a wireless cab block-signal system, a track divided into blocks, each block constituting a track-circuit, devices near said blocks for propagating electrical oscillations through space, energizing-circuits for said oscillation devices, relays in said track-circuits for controlling said energizing-circuits, said relays being of different resistances, the relay of higher resistance controlling the energizing-circuit of the propagating device and the relay of lower resistance controlling an advance track-circuit, said relays controlled by a train in a preceding block, and a receiving device on the train responsive to said oscillations to give notice of the condition of a block in advance of the train.

HERBERT B. TAYLOR.

Witnesses:

J. GREEN,
A. P. KNIGHT.

It is hereby certified that in Letters Patent No. 739,518, granted September 22, 1903, upon the application of Herbert B. Taylor, of Newark, New Jersey, the title of the invention was erroneously written and printed "Railway Block-Signaling System," whereas the said title should have been written and printed *Wireless Cab Block-Signal System*; and that the said Letters Patent should be read with this correction therein that the same may conform to the record of the case in the Patent Office.

Signed and sealed this 6th day of October, A. D., 1903.

[SEAL.]

F. I. ALLEN,
Commissioner of Patents.
